JOHN H. DOMKEE, OF WEST HAVEN, CONNECTICUT, ASSIGNOR TO THE WIRE NOVELTY MANUFACTURING CO., OF WEST HAVEN, CONNECTICUT, A CORPORATION OF CONNECTICUT

SLIDE BUCKLE

Application filed February 15, 1929. Serial No. 340,247.

The invention relates to that class of buckles known as "slides" and used for adjusting the length of straps, webbing, and the like, without penetrating the material, and the object of the invention is to provide a reversible slide having fixed intermediate bars independently formed with spaced humps projecting in opposite directions along planes perpendicular to the plane of the slide. With this and other objects in view as may become apparent from the within disclosures the invention consists not only of the particular form herein pointed out and illustrated in the drawing but readily admits of certain modifications within the scope of what hereinafter may be claimed.

The following is the description of an embodiment of the invention, reference being had to the accompanying drawing in which the Figure 1 is a face view of the slide buckle; the Figure 2 is a bottom view; and the Figure 3 is a side elevation.

Referring more particularly to the drawing in which similar numbers refer to similar parts the slide buckle, while illustrated as made of wire, may be stamped from sheet metal or made in any other desired manner, but as illustrated the buckle is made from a single piece of wire and comprises the pair of loops 1 and 2 connected at one side by the side-bar 3 and free at the other side, the loops 1 and 2, including the side-bar 3, being arranged in the same plane. Intermediate bars 4 and 5 extend integrally from the free side of the loops across the buckle to the connected side thereof and are independently made in an undulating form with relatively staggered high points, each bar being thus corrugated to provide a central hump 6 projecting from opposite faces of the loops in an opposite direction, one from the other, and along planes perpendicular with the plane of the loops, and each bar further providing spaced humps 7, the humps 7 of one bar projecting from opposite faces of the combined loops in an opposite direction from that of the humps 7 of the other bar, and the humps 7 of each bar projecting from opposite faces of the combined loops in an opposite direction from that of the hump 6 of the same bar, the humps 7

being spaced from their respective sides of the loops. The ends of the bars 4 and 5, being the two ends of the single piece of wire from which the buckle is made, may be welded to the side-bar 3 if desired. It is therefore apparent that the undulated or corrugated bars 4 and 5, relatively staggered and thus co-operating to form spaced humps projecting from opposite faces of the combined loops, provide a reversible slide buckle adapted to receive a strap to be threaded thereinto in the usual manner without regard to the relative positions of the slide buckle and the strap, the spaced humps, projecting out of the plane of the combined loops, being adapted to offset the threaded strap to bind it therein when the remaining portion of the strap adjacent the slide buckle is substantially in the plane of the combined loops.

What I claim is:—

1. A slide buckle having a pair of loops connected at one side and free at the opposite side, and intermediate bars extending integrally from the free side of the loops and being provided with spaced single peaked humps projecting out of the plane of the buckle, the free ends of the bars engaging the side connection.

2. A reversible slide buckle having a pair of loops connected at one side and free at the opposite side, and intermediate fixed bars extending integrally from the free side of the loops and being provided with spaced single peaked humps projecting out of the plane of the buckle in both directions, the free ends of the bars engaging the side connection.

3. A reversible slide buckle having a pair of loops connected at one side and free at the opposite side; intermediate bars having their free ends engaging the side connection; and peaked humps provided by both bars, the peaked humps of one bar alternating with the peaked humps of the other bar to provide spaced peaked humps projecting out of the plane of the buckle in one direction and also spaced peaked humps projecting out of said plane in the other direction.

4. A slide buckle of rectangular form having an upper bar, a lower bar, and side bars; and intermediate fixed and angularly bent

100

bars extending from one side to the other side of the buckle, the angular bends of one bar alternating with the angular bends of the other bar to provide spaced peaked humps projecting out of the plane of the buckle in opposite directions.

5. A reversible slide buckle comprising a single piece of wire of which a middle portion is bent to form a pair of loops connected at one side and free at the opposite side, the remaining end portions of the wire extending across the buckle from the free side that their free ends may engage the side connection, said wire end portions being first bent out of the plane of the buckle, each in opposite directions, and each further bent, relatively crossed and recrossed to alternately provide spaced peaked humps projecting from the plane of the buckle in both directions.
10. A reversible slide buckle having a pair of loops connected at one side and free at the opposite side; intermediate fixed bars extending integrally from the free side of the loops, the free ends of the bars engaging the side connection; and spaced single-peaked humps provided by one of the bars and projecting in opposite directions out of the plane of the buckle.
15. A reversible slide buckle having a pair of loops connected at one side and free at the opposite side; intermediate fixed bars extending integrally from the free side of the loops, the free ends of the bars engaging the side connection; and spaced single-peaked humps provided by one of the bars and projecting in opposite directions out of the plane of the buckle.
20. A reversible slide buckle having a pair of loops connected at one side and free at the opposite side; intermediate fixed bars extending integrally from the free side of the loops, the free ends of the bars engaging the side connection; and spaced single-peaked humps provided by one of the bars and projecting in opposite directions out of the plane of the buckle.
25. A reversible slide buckle having a pair of loops connected at one side and free at the opposite side; intermediate fixed bars extending integrally from the free side of the loops, the free ends of the bars engaging the side connection; and spaced single-peaked humps provided by one of the bars and projecting in opposite directions out of the plane of the buckle.
